UNITED STATES PATENT OFFICE.

THOMAS L. ROBERTSON, OF DANVILLE, VIRGINIA.

INKSTAND.

1,345,959.

Specification of Letters Patent.

Patented July 6, 1920.

Application filed November 14, 1918. Serial No. 262,584.

To all whom it may concern:

Be it known that I, THOMAS L. ROBERTSON, a citizen of the United States, residing at Danville, in the county of Pittsylvania and State of Virginia, have invented new and useful Improvements in Inkstands, of which the following is a specification.

It is the purpose of the invention to provide a device of the character mentioned adapted for the holding of an ink container and keeping the same covered when the ink is not being used, the construction being such that a writer has but to operate the raising means of the cover of the container to reach the ink, the said cover being automatically returnable to closing position upon release of its raising means.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:

Figure 1 is a side elevation of the device showing the parts in a closed position.

Fig. 2 is a top plan view thereof.

Fig. 3 is a fragmentary sectional detail showing the parts in a closed position.

Fig. 4 is a similar view showing the parts in an open position.

Similar characters of reference are employed in all of the above described views, to indicate corresponding parts.

Referring now, more particularly, to the accompanying drawings there is provided a base 1 from which projects upright retaining posts 2 joined at their upper ends by a substantial spider 3 which coöperates with the posts in forming a substantial retaining frame for the ink container generally indicated 4. Now this container consists of a lower section 5 and an upper section 6 which is of an inverted frusto-conical form and 55 is preferably detachably connected as by threads 7 to the correspondingly formed

upper edge of the section 5. The upper section terminates in a neck 8 about which is disposed the central ring portion 9 of the spider 3, the arms 10 of the spider, of course, being joined with the posts 2.

A secondary post 11 extends upwardly from one of the arms 10 of the spider 3 while the lever 12 is swingingly connected as at 13 to the upper end thereof, one end of the lever being bent to provide a depending portion 14 and this depending portion carries a cover 15 designed for engagement with the upper edge of the neck 8 of the upper section 6 of the container for closing the container.

Suitable means such as a coil spring 16 is now employed and has its respective ends connected to the lever 12 near the bent portion 14 and to one of the arms 10 serving to normally hold the cover in yielding engagement with the neck 8.

In order to raise the cover one of the posts is formed with an extension 17 while swingably connected to the upper end thereof as at 18 is a ring like portion 19 of a lever 20. A cross bar 21 extends across the ring portion of the lever 20 and is disposed over and rests upon the free end portion of the lever 12 while the outer end of the lever 20 terminates in a finger ring 22 which when depressed causes a pressure to be exerted by the cross bar 21 on the free portion of the lever 12 swinging the latter lever about its pivot for the raising of the cover 15 from the neck 8 and against the tension of the spring 16. It is apparent that the pen of the writer may be held in the hand which is used to depress the lever 20 and when the cover 15 is raised it is only necessary to insert the pen (not shown) within the neck 8.

Floatably supported by the ink in the neck 8 is a hollow closure disk 23 formed with a central pen point engaging opening 24 through which the pen point (not shown) is adapted to pass when being dipped in the ink beneath the disk.

It is believed in view of the foregoing description that a further detailed description of the operation of the invention is entirely unnecessary. Likewise it is believed that the advantages of the invention will be readily apparent.

What is claimed is:

A device of the character described including a base, a container thereon formed with a neck, a retaining frame for the con-

tainer including upright posts projecting from the base and a spider the ring portion of which is disposed about the neck of the container while the arms are joined with the posts, a secondary post on one of the arms of the spider, a lever swingably connected to the secondary post, a cover suspended from the lever for seating against the neck, one of the posts of the frame being higher than the others, another lever formed with a ring like portion swingingly connected to the high post, a cross bar across the

ring like portion of the second lever and seated and supported on the free portion of the first lever so that when the second lever is depressed the first lever will also be depressed for the raising of the cover, and a coil spring connected to the frame and to the first lever and tensioned so as to normally hold the cover seated and for automatically returning the parts to their normal positions subsequent to the release thereof.

In testimony whereof I affix my signature.

THOMAS L. ROBERTSON
